INVENTOR.

Rudolf Klein,
BY
Everett Rock, ATTORNEYS.

UNITED STATES PATENT OFFICE.

RULOF KLEIN, OF MONTCLAIR, NEW JERSEY.

SIPHON-TUBE BASE.

Application filed May 27, 1921. Serial No. 473,174.

To all whom it may concern:

Be it known that I, RULOF KLEIN, a citizen of the United States, and a resident of Montclair, in the county of Essex and State 5 of New Jersey, have invented new and useful Improvements in Siphon-Tube Bases, of which the following is a specification.

This invention relates in general to tubes or pipes utilized for drawing liquid from 10 a container having sediment or foreign matter at the bottom thereof, and more particularly to a base or terminal for such tubes or pipes to prevent the said sediment or solid matter from entering the tube or pipe 15 and enabling only clear liquid to enter the same.

The objects of the invention are to provide a base or terminal of the character described embodying novel features of construction whereby clear liquid may be drawn from the extreme bottom of a container containing sediment or foreign matter; to provide a cup-shaped member having a rigid upstanding projection on its 20 bottom within the rim to receive the end of an elastic tube or pipe, said projection being formed to permit passage of liquid from the interior of said cup-shaped member into said tube or pipe, the sides of said member 25 excluding foreign matter from the interior thereof; to provide an improved construction for said projection to receive the end of a tube or the like whereby ample clearance between said tube and said projection 30 for the passage of liquid is provided; to provide in such a device means for limiting the movement of the tube or pipe onto said projection and maintain the end of said tube or pipe in spaced relation to the 35 bottom of said cup-shaped member to permit passage of liquid from within the said member into said tube; and to obtain other results and advantages as may be brought 40 out by the following description.

Referring to the accompanying drawings, in which like numerals of reference indicate the same parts throughout the several views,

Figure 1 is a vertical sectional view 45 through a container showing the manner of utilizing my improved base or terminal in connection with a tube or pipe for withdrawing clear liquid from the container;

Figure 2 is a transverse vertical sectional

view through the base taken on the line 2—2 55 of Fig. 4;

Figure 3 is a transverse sectional view taken through the base on the line 3—3 of Fig. 4;

Figure 4 is a top plan view of the base; 60

Figure 5 is a horizontal sectional view through the projection of the base for receiving the end of the tube or pipe, taken on the line 5—5 of Fig. 3.

For the purpose of illustrating the uses 65 of my invention I have shown the base or terminal A connected to the end of a flexible tube B and utilized for withdrawing clear liquid from a container C, such as a crock, which has sediment or foreign matter 70 D at the bottom thereof.

The base A is substantially circular and comprises a disk-like body portion 1 provided with an upstanding annular wall 2 on one side thereof, the body portion 1 being adapted to rest upon the bottom of the container with the annular wall 2 projecting upwardly through the sediment in the container to a point above the surface of the sediment as shown in Figures 1 and 2. 75 The base A is thus substantially cup-shaped and is preferably formed of a heavy material which will cause the base to sink by gravity to the bottom of a container. Arranged substantially axially of the body 1 and within the annular upstanding wall 2 is a projection 3 which serves to connect the base A to the end of a tube, pipe, or the like. In the present instance I have shown the base A used in connection with a flexible tube B, and the tube is connected to the base by telescopically forcing the end of the tube over the projection 3, as shown in Figures 2 and 3, the tube being held in position by friction. In 80 Figures 2, 3, 4 and 5 the projection 3 is shown as substantially rectangular in cross-section and formed with longitudinal grooves 4 in opposite sides thereof which extend the full length of the projection, 85 and merge into the body portion 1 of the base within the annular upstanding wall 2. These grooves 4 thus provide clearance between the projection 3 and the walls of the tube B, as clearly shown in Figures 2 and 90 5, so that the liquid in the container C can pass into the end of the tube B as indicated by the arrows. For the purpose of pre-

venting the end of the tube B from being slipped over the projection 3 into engagement with the body portion 1 of the base so as to prevent liquid from entering the 5 tube, the projection 3 is provided at a point intermediate its length with shoulders 5 which are engaged by the end of the tube as it is slipped over the projection 3.

With this construction it will be seen that 10 the upstanding annular wall 2 of the base will prevent the sediment or foreign matter D from entering within the annular wall and passing into the tube B, and at the same time the end of the tube is positioned 15 in close proximity to the bottom of the container and even below the surface of the sediment. The clear liquid can thus flow over the top of the wall 2 and then downwardly below the end of the tube B 20 and upwardly through the grooves 4 in the projection 3 out of the container to a desirable point.

A base constructed in accordance with my 25 invention is particularly adaptable for use with flexible and elastic siphon tubes, such as a rubber tube, the base being constructed to rest by action of gravity upon the bottom of the container and penetrating the sediment therein whereby clear liquid may be 30 withdrawn from the extreme bottom of the container and the sediment of foreign matter completely excluded from the siphon tube. The rigid projection 3 enables an elastic 35 tube to be easily and quickly slipped over it and the base 1 is held on the tube by the elasticity and frictional engagement of the tube with said projection, whereby the base can be quickly attached to and removed from a tube and interchangeably used with a number 40 of tubes of substantially the same diameter. Further, the base embodying the invention can be molded or cast in one piece in one operation and without the use of undercuts or special cores, so that the cost of manufacture is small. There are no cracks or 45 corners in the device and all parts thereof are clearly accessible so that it can be easily and thoroughly rinsed and cleaned.

While I have shown and described one 50 preferred embodiment of my invention, it will be understood that this is for the purpose of illustrating the principles thereof only, and that many modifications and changes can be made in the detail construction 55 of the device without departing from the spirit or scope of the invention. The base has been shown as used in connection with a flexible tube, but it will be understood that it is also adaptable for use with pipes 60 and the like which are utilized for drawing clear liquid from a container, well, or the like, having sediment in the bottom thereof. Therefore, I do not desire to be understood 65 as limiting myself in the construction or use

of my invention except as required by the 65 following claims construed in the light of the prior art.

Having thus described the invention, what I claim is:

1. In a siphon tube, the combination of an 70 elastic tube, and a base comprising a cup-shaped body portion having a rigid upstanding projection on the bottom thereof, said projection being adapted to telescopically and frictionally receive said tube thereover 75 and being formed with passages to permit flow of liquid between itself and said tube, said base and said tube being maintained in said connected relation by the elasticity and frictional engagement of said tube with 80 said projection.

2. In a siphon tube, the combination of an 85 elastic tube, and a base comprising a cup-shaped body portion having an integral solid and rigid upstanding projection on the bottom thereof to telescopically and frictionally receive said tube thereover, said projection being formed with a longitudinal interior 90 groove to permit liquid to flow between said tube and said projection, and said base and said tube being maintained in said connected relation by the elasticity and frictional engagement of said tube with 95 said projection.

3. A device of the character described 100 comprising a cup-shaped body portion having a single rigid upstanding projection on the bottom thereof to telescopically receive a tube or pipe thereover, said projection being formed with passages merging into the bottom of said body portion to permit liquid to flow from within said body portion between said projection and said tube into 105 said tube.

4. A device of the character described 110 comprising a cup-shaped body portion having a single integral solid and rigid upstanding projection on the bottom thereof to telescopically receive a tube or pipe thereover, said projection being formed with an exterior longitudinal groove merging into 115 said bottom of the body portion to permit liquid to flow from within said body portion between said projection and said tube into said tube.

5. A device of the character described 120 comprising a body portion having a continuous upstanding wall and a solid rigid upstanding projection within said wall adapted to telescopically receive the end of a tube or pipe, said projection being formed with a longitudinal exterior groove and a shoulder intermediate the ends of said groove to limit the movement of said tube onto said projection, said groove permitting the passes of 125 liquid from within said wall between said projection and said tube or pipe into said tube or pipe.

RULOF KLEIN.
